UNITED STATES PATENT OFFICE.

ALFRED T. CHARLIER, OF LUXEMBOURG, WISCONSIN.

DESIGN FOR A COMBINATION CAP AND BOTTLE OPENER, BOX-OPENER, AND CIGAR-CUTTER.

55,843.

Specification for Design.

Patented July 20, 1920.

Application filed July 24, 1919. Serial No. 313,111. Term of patent 7 years.

To all whom it may concern:

Be it known that I, ALFRED T. CHARLIER, a citizen of the United States, residing at Luxembourg, in the county of Kewaunee, State of Wisconsin, have invented a new, original, and ornamental Design for a Combination Cap and Bottle Opener, Box-Opener, and Cigar-Cutter, of which the following is a specification, reference being had to the accompanying drawings, forming part thereof.

Figure 1 is a perspective view of a combination cap and bottle opener, box opener and cigar cutter showing my design, and Fig. 2 is a fragmentary perspective view looking at the opposite side.

The device embodies a ring-like structure

having a cork screw at one side and at the opposite side, a bottle cap opener, while intermediate portions are provided with a blade for opening cigar boxes and a cigar cutter to clip the end of a cigar, which cutter is provided with a projection to push the nail for fastening a cigar box cover out of position to remove the same.

I claim

The ornamental design for a combination cap and bottle opener, box opener and cigar cutter as shown and described.

ALFRED T. CHARLIER.
